SAWMILL CARRIAGE

Luther Robert Stanley and Walter Henry Pate,
Greggton, Tex.

Application October 10, 1946, Serial No. 702,464

5 Claims. (Cl. 143—108)

1

This invention relates to a saw mill log carriage and more particularly to a saw mill log carriage having the source of motive power supported thereon.

It is an object of this invention to provide an improved saw mill log carriage which may be operated completely by an operator seated on the carriage, thus eliminating the necessity of a block setter and signalman, thereby increasing the speed and efficiency of the sawing operation.

Another object of this invention is to provide a saw mill log carriage of the kind to be more particularly described hereinafter, in which a motor is carried on the carriage which motor may be controlled by an operator on the carriage, and winding drums driven by the motor for pulling the carriage in either direction along the track.

Still another object of this invention is to provide a novel gear arrangement for propelling a saw mill log carriage along its supporting tracks which consists of a pair of winding drums driven by a motor through a separate differential gearing for each drum, the speed of rotation of each drum being controlled by a clutch or brake on the differential gear arrangement whereby the drum is rotated when the clutch or brake is held against rotation or retarded a certain degree by the operator riding on the carriage.

Yet another object of this invention is to provide a saw mill log carriage of this kind in which a wire rope or cable is utilized for propelling the carriage with less spring than the conventional arrangement of a line running over a sheave whereby better control of the carriage is obtained.

A further object of this invention is to provide a self propelled log carriage for saw mills, which is more readily and finely controlled in speed in each direction by the operator thereon which permits of the most advantageous and time saving production under varying conditions.

With the above and other objects in view, our invention consists in the arrangement, combination and details of construction disclosed in the drawings and specification, and then more particularly pointed out in the appended claims.

In the drawings,

Figure 1 is a top plan view, partly broken away and partly in section, of our log carriage,

Figure 2 is a front elevation thereof.

Figure 3 is a transverse section taken on the line 3—3 of Figure 1.

Figure 4 is a diagrammatic view of the drum and cable arrangement.

Referring to the drawings, the numeral 10 designates generally a saw mill log carriage constructed according to an embodiment of our invention. The carriage 10 is formed with a base

2

having longitudinally extending channeled side members 11, and transverse members 12 connected between the side members 11. On the forward side of the frame or base, wheels 14 are provided for engaging on a rail or track 15 for supporting the carriage 10, and wheels 16 are rotatably carried by the frame on the rear side which engage on the rail 17. The front rail or track 15 is formed with an inverted V-shaped upper surface and the wheels 14 are each formed with a V-shaped peripheral edge or groove engageable on the V-shaped rail 15 to hold the carriage 10 against movement off of the rails transversely of the rails 15 and 17. The rear rail 17 is provided with a wear resisting surface 18 on its upper edge on which the flat rimmed wheels 16 engage. Axles or shafts 19 are carried by bearing brackets 20 fixed on and hung from the frame for rotatably supporting the axles 19 and wheels 14 and 16. The wheels 14 and 16 are freely rotatable relative to the frame, there being no driving connection to the wheels.

Transverse supporting members 21 are fixed on the frame between the members 11 on the upper side thereof and L-shaped log blocks 24 are slidably along the length of the members 21 transversely of the carriage 10 for pushing the logs forwardly where they may be cut by the circular saw blade 25 which is supported and rotated independently of the carriage 10.

At each end of the tracks 15 and 17, there is provided a raised block or tie 26 extending between the rails and midway the lengths of the blocks 26 a steel rope or cable 27 is anchored, the rope 27 being relatively taut whereby there will be little stretching and slipping as the carriage propels itself along the tracks and rope in the manner to be hereinafter described.

The log blocks 24 are slidably moved across the carriage 10 by an operator seated in the seat 28, fixed on the carriage, through the control levers 29 and 30.

The conventional way of propelling a carriage of this type along the track is to provide a fixed source of power and a winding drum with a cable or rope about the drum fixed to the carriage. With such an arrangement it is necessary to have an operator for the cable and another operator on the carriage and a signal system whereby the operator on the carriage may inform the operator of the winding drum of the necessity for a change in speed or direction. Such an arrangement is clumsy and inefficient as compared to the improved power system of our invention.

In order to provide a motive power for the carriage 10, we have provided a gasoline or other suitable engine or prime mover 31, fixed on the upper surface of the carriage frame and provided with a throttle lever 32 which the operator

may reach while seated on the carriage 10. The engine 31 rotates directly a drive shaft 34 on which is fixed a sprocket 35, the shaft 34 being supported on the carriage frame by bearing brackets 36.

An intermediate or counter shaft 37 is rotatably supported on the frame between bearing brackets 38 and has fixed thereon three sprockets 39, 40 and 41. The center or drive sprocket 40 is driven by a chain 42 about the sprockets 35 and 40. The engine is adapted to turn in but one direction to drive the chain 42 in the direction shown by the arrow adjacent thereto. Rotation of sprocket 40 effects simultaneous rotation of sprockets 39 and 41.

Drums 43 and 44 are driven by the engine 31 in opposite directions as indicated by the arrows thereon for propelling the carriage 10 in the desired direction as the cable 27 is coiled about the drums so that rotation of the drum being driven causes the carriage 10 to move in the certain direction. The drum 43 is driven through the differential gearing 45 and the drum 44 is driven by the differential gearing 46. The gearing 45 comprises a sprocket 47 fixed to a short longitudinal shaft 47' rotatably supported on the carriage which is driven by a chain 48 about the sprockets 41 and 47. A driving pinion gear 49 is fixed on the same shaft as the sprocket 47 and is driven thereby. The driving pinion 49 engages the outer ring gear 50 for constantly driving the gear 50 at a constant speed. Ring gears 51 and 52 are driven by the pinions 54 rotatably carried by the outer ring gear 50. The drum 43 is fixed on the same shaft 55 as the gear 51 and a brake or clutch plate 56 is fixed on the same shaft 57' as the ring gear 52. With no load on the drum 43 or clutch plate 56, or an even load on both, the drum 43 and clutch plate 56 are rotated in the same direction as indicated by the arrow. When the friction of the cable 27 is put on the drum 43, the drum 43 is held against rotation and the clutch plate 56 is rotated in the same direction at twice the original speed, and when a load as by a brake band 57 is put on the clutch plate 56, the drum 43 is rotated, the speed of the rotation of the drum 43 varying inversely as the speed of the clutch plate 56 reaching a maximum when the clutch plate 56 is stopped by the brake band 57.

The same arrangement is provided for rotating the drum 44, namely, the chain 58 drives the sprocket 59 which in turn drives the driving pinion 60 fixed on the same shaft. The pinion 60 meshes with and drives the outer ring gear 61 which in turn rotates the inner ring gears 62 and 64 through the pinions 65. The drum 44 is fixed on the same shaft 66 as the gear 62 and the clutch plate 67 is fixed on the same shaft 68' as the ring gear 64. Rotation of the drum 44 and clutch plate 67 is in a direction opposite to that of the drum 43 and clutch plate 56, and the rotation of the drum 44 and its speed is controlled by the brake band 68 engaging clutch plate 67 in the same manner as brake band 57 engages clutch plate 56.

The brakes or brake bands 57 and 68 are controlled by an operator seated in the seat 28 on the carriage 10. A pedal 69 is connected to the brake band 57 by rods 70 and 71 connected together by a bellcrank 72, and pedal 74 operates brake band 68 through rods 75 and 76 and bellcrank 77, whereby depression of the pedals 69 and 74 cause the brake bands 57 and 68 to engage and hold or brake the clutches or clutch plates 56 and 67 respectively.

In the use and operation of this saw mill log carriage 10, the engine is run at a constant speed by an operator seated on the carriage 10. Through the sprocket and chain drives as shown in Figure 1, the outer ring gears 50 and 61 are driven at a constant speed in opposite directions. Since the cable 27 is wrapped about the drums 43 and 44, the drums are held against rotation and the clutches or clutch plates 56 and 67 are rotated at twice the speed of the ring gears 50 and 61 respectively.

When it is desired to move the carriage 10 to the right, as seen in Figure 1, the pedal 69 is depressed which causes band 57 to tighten on and hold or brake the clutch plate 56 causing drum 43 to rotate in the direction indicated, thus wrapping the cable about the drum 43 and paying it out to the left over drum 44 which is idling at this time. To move the carriage 10 to the left, the pedal 69 is released and pedal 74 depressed. Brake band 68 holds clutch plate 67 against rotation, thus rotating drum 44 as indicated and paying out the cable 27 over drum 43 which is now idling. The speed of the drums 43 and 44 is controlled by the pressure on the brakes or brake bands 57 and 68 respectively, being a maximum when the brakes or brake bands are fully set holding the clutches or clutch plates against rotation. The different diameters of the drums 43 and 44 cause feeding more slowly in the sawing direction than in the return movement.

We do not mean to confine ourselves to the exact details of construction herein disclosed, but claim all variations falling within the purview of the appended claims.

What we claim is:

1. A saw mill log carriage adapted to run on a track comprising a frame, an engine on said frame, a pair of winding drums on said frame, a single length of cable anchored at its ends to opposite ends of the track and looped around both drums in the same direction, a differential drive gear arrangement for each of said drums for rotating said winding drums in opposite directions, a clutch plate on each of said differential gear drives opposite from the drum thereon, a brake for each of said clutch plates for checking rotation of the clutch plates for independently driving the drums to advance the carriage in a cutting direction and to return the same, operable means driving said differential drives from said engine, whereby each of said drums is caused to rotate upon braking of the respective brakes.

2. A saw mill log carriage adapted to run on a track comprising a frame, an engine on said frame, a pair of oppositely rotating winding drums on said frame, a single length of cable anchored at its ends to opposite ends of the track and looped around both drums in the same direction, a differential gear drive for each of said drums, means for driving said differential gears from said engine, each of said differential gears comprising an outer ring gear, pinions on said outer ring gear, a pair of inner ring gears engaging said pinions, and a driving pinion gear engaging said outer ring gear, one of said winding drums connected to one inner ring gear in each of said differential drives, a clutch plate fixed to the other of said inner ring gears, and a brake for each of said clutch plates for holding a selected one of said clutch plates against rotation for rotating the respective winding drum associated therewith.

3. Propelling means for a saw mill log carriage

comprising a length of track, a single cable secured at each end of said track and extending longitudinally thereof, a carriage on said track, an engine on said carriage, a pair of winding drums journaled on said carriage and driven by said engine, a differential gear for each of said winding drums for rotating said drums in opposite directions, said cable being looped about each of said drums in the same direction, a clutch on each of said differential gears opposite from the drum thereon, and a brake for each of said clutches for independently driving said oppositely rotating drums and controlling and reversing the direction of movement of said carriage.

4. A saw mill comprising tracks, a log carriage movable on the tracks, a saw supported and rotated independently of the carriage, an engine on said carriage, a pair of winding drums of different diameters journaled on said carriage, a single length of cable anchored at its ends at opposite ends of the track and looped around both drums in the same direction, a differential drive gear for each of said drums for rotating said drums in opposite directions, a clutch plate on each of said differential gears at the sides thereof opposite to the drums, a brake band for each of said clutch plates for checking rotation of the clutch plates for independently driving the drums to advance the carriage in a cutting direction by the smaller drum more slowing than in a return direction by the larger drum, operative drive connections between the engine and the differential gears and means for independently engaging a brake band with a clutch plate to cause independent rotation of the drums in opposite directions.

5. A saw mill comprising a base having tracks,

a saw supported and rotated independently, a log carriage movable back and forth on the tracks, an engine on said carriage, a pair of oppositely rotatable winding drums of different size mounted on the carriage, a differential drive for each of said drums to drive the drums in opposite directions, means for driving the differentials from the engine, means oppositely driven by each of said differentials, means for checking either of the driven means to independently drive the drums in opposite directions, a cable anchored at its ends on the base and looped around both of said drums in the same direction for moving said carriage in opposite directions upon independently driving said drums in opposite directions, the size of said drums varying the speed of movement of the carriage on the base in opposite directions of travel.

LUTHER ROBERT STANLEY.
